UNITED STATES PATENT OFFICE.

JOHN G. BORN AND GEORGE J. BORN, OF PITTSBURG, PENNSYLVANIA.

IMPROVEMENT IN SCREW-CUTTING DIE-CHUCKS.

Specification forming part of Letters Patent No. **179,677**, dated July 11, 1876; application filed June 6, 1876.

To all whom it may concern:

Be it known that we, JOHN G. BORN and GEORGE J. BORN, of Pittsburg, in the county of Allegheny and State of Pennsylvania, have invented a new and Improved Die-Chuck, of which the following is a specification:

The invention consists of the two parts of a divided screw cutting die, fixed on slides, which are fitted in a supporting-plate and combined with an eccentric and shaft in such manner that the die is opened and closed readily by the eccentric.

Figure 1 is an elevation of our improved die-chuck. Fig. 2 is a section on the line *y y*; and Fig. 3 is a section on the line *x x*.

Similar letters of reference indicate corresponding parts.

A represents a supporting plate or stock, in which the plate *B*, having one-half of the die *C*, is fitted in dovetail or equivalent grooves to slide forward and backward a little. *D* is another plate, having part *E* of the die attached to it, and being fitted to slide in plate *B*. *F* is an eccentric on shaft *G*, fitted in bearings at *I* in plate *B*, and also extended through elongated bearings *J* in the supporting-plate

A, in which it is free to move to allow plate *B* to be adjusted to the hole *K* in the supporting-plate for the rod or tube to be screw-threaded. The shaft *G* is fitted at *K* for the application of a crank for turning it to open and close the die, which it accomplishes by pushing against plate *D* at *L* and *M*. *N* is a groove cut in the plate *B*, under the meeting point of the dies, to allow the chips to fall out so as not to clog between the dies, and the opening between the dies is made a little wider at the lower side for the same purpose. *R* is a stop-screw for preventing the plate *D* from sliding too far either way.

Having thus described our invention, we claim as new and desire to secure by Letters Patent—

The combination of the independently-sliding die-plates *B* and *D*, supporting-plate *A*, shaft *G*, and eccentric *F*, substantially as specified.

JOHN G. BORN.
GEORGE J. BORN.
